UNITED STATES PATENT OFFICE.

LESTER O. NAYLOR, OF NEW YORK, N. Y., ASSIGNOR OF ONE-HALF TO OTTO HAUERBACH, OF NEW YORK, N. Y.

HEATER FOR AUTOMOBILES.

1,069,572.

Specification of Letters Patent. Patented Aug. 5, 1913.

Application filed May 10, 1912. Serial No. 696,489.

To all whom it may concern:

Be it known that I, LESTER O. NAYLOR, a citizen of the United States, and residing at New York, in the county and State of New York, have invented certain new and useful Improvements in Heaters for Automobiles; and I do hereby declare the following to be a full, clear, and exact description of the same, reference being had to the accompanying drawings, forming part of this specification, and to the figures and letters of reference marked thereon.

This invention relates to apparatus for supplying heat to the passenger space or spaces of an automobile vehicle from a portion or all of the hot exhaust gases from the motor. Various heating arrangements adapted for the circulation of the exhaust gases have been proposed, but such prior apparatus has usually required more or less extensive alteration in the mechanism, framework, flooring or bodies of the vehicles.

The object of the present invention is to provide an exceedingly simple form of apparatus which may be readily installed in practically any type of pleasure or commercial vehicle without the necessity of any alteration or change in any portion of the vehicle itself further than the perforation of the flooring for the passage of the pipes through which the heated gases pass to and from the heater.

Referring to the accompanying drawings,—Figure 1 is an elevation looking at the rear of an automobile with the tonneau seats removed and portions broken away to show the heater and its connections; Fig. 2 is a view showing in end elevation the heater which is located in the front portion of the tonneau just above the floor line, this view also showing a portion of the main exhaust pipe from the motor and the heater valve. Fig. 3 is a front elevation of the preferred form of heater showing in dotted lines the reverse bend at the end remote from the exhaust pipe connection and with portions broken away; Fig. 4 is a section on the line 4—4, Fig. 3; Figs. 5 and 6 are detail views of the valve controlling and passage of exhaust gases to the heater and the operating lever therefor.

Like letters of reference in the several figures indicate the same parts.

55 Referring particularly to Fig. 1, it will be

seen that the conventional parts of the vehicle are represented, the view showing the back portions of the front seats. The usual exhaust pipe A extends back beneath the floor of the body and is preferably provided with the usual muffler B of known construction. At a point preferably forward of the muffler, the exhaust pipe or duct A is provided with a lateral branch C, and at the junction of the branch and main duct A a valve is located and adapted to be operated by a lever or arm D, as will be presently described so as to control the flow of gases through the branch duct. The branch duct C extends upwardly through the floor of the vehicle, but preferably has incorporated in it a union E, and at the upper end it joins the heater pipes which extend transversely above the floor of the vehicle and are preferably in two lengths E and E', arranged parallel and one above the other. Said pipes are connected at their farther ends by a reverse bend e, and the lower section E' at its end nearest the branch C is carried down by means of an elbow coupling e' and connected with a pipe discharge e² which preferably leads into the open air, as shown, but may be carried away to any suitable point and connected with the main exhaust pipe.

In the preferred arrangement the heater pipes are supported above the floor and out of any direct contact with the body of the vehicle, while contact of robes, garments or the feet of the passengers with the heater pipes is prevented and a finished appearance given the structure by a shield which preferably takes the form of an oval in cross section with one side of the oval for the free circulation of air about the pipes. As shown, the shield F is made of sheet metal of ornamental form and it is spaced from the heater pipes, being mounted in end brackets G and connected with the pipes by clips F' held by screws F² passing between the pipes.

The heater occupies the most convenient position for a foot rest and to afford a firm rest against which the passengers may brace themselves, a foot rest or bar H is arranged in position immediately in rear of the heater, as shown clearly in Figs. 1 and 4, the preferred location of the bar being such that the feet of the passengers will be held in an inclined position upwardly over the heater.

so as to obtain the full benefit of the heat radiated from the heating pipes and shield. The bar H not only forms the foot rest, but constitutes a part of the heater itself; thus 5 it is preferably provided with a longitudinal channel h for the reception of the edge of the shield, and at its ends it is connected with the end bracket G, in which the ends of the shield are confined. The connection 10 between the bar and brackets may conveniently be formed by screws h' passing through the brackets and into the ends of the bar as will be readily understood. The lower edge of the shield is also preferably 15 strengthened by an edge bar L having a channel for the shield edge and connected with the end brackets by screws or other fastening means. When desired the shield may also be connected with the end brackets as 20 by angle pieces M and screws as shown.

The flow of exhaust gases from the exhaust pipe through the heater is controlled by a valve D² located at the junction of the heater branch with the main exhaust pipe, 25 said valve being so constructed that as the heater branch is opened the main exhaust pipe is correspondingly restricted at a point just beyond the branch, thereby diverting a portion of the gases through the heater 30 and at the same time avoiding any material increase in the resistance to the flow of the gases which might cause back pressure and cut down the power of the engine.

The construction of the valve will be 35 readily understood from Figs. 5 and 6, wherein it will be seen that the body or housing D of the valve has a transverse cylindrical chamber d into which the main and branch exhaust ducts open at an angle to 40 each other, and within the chamber is a segmental valve gate D'. The cylindrical face of the gate is of such size as to completely close the branch duct opening when turned to proper position, and when the gate is 45 swung to open or partly open the branch it correspondingly closes or partly closes the main exhaust pipe beyond the branch. The valve gate is journaled in bearings in the ends or heads of the body, one of which may 50 be removable, and a lever arm D secured to the valve gate serves as the means whereby the gate may be adjusted.

In the preferred arrangement the arm D is connected by suitable link or rod connections n with an operating lever or arm O pivotally mounted on a sector O' secured on the back of the front seat or other convenient part of the vehicle body where it may be reached by the passenger. The sector and operating lever have a series of stop points of known construction for holding the parts in the position to which they have been adjusted.

From the foregoing, it will be seen that 65 the heating apparatus is of such character

that it may be readily installed in practically any make or construction of automobile without requiring any alteration of either the mechanism, body or framing. It forms not only an efficient heater but constitutes a foot rest of approved character which is ornamental and in keeping with the style of the most approved types of vehicle. The heaters may be made of standard size and the only fitting which is necessary for each installation is the ordinary pipe connection between the heater and the exhaust pipe branch. This may require longer or shorter nipples or pipe sections, as the case may be, for different types of vehicle, but sections of pipe of standard size are readily available and it therefore becomes possible for an ordinary mechanic to install one of the heaters in any vehicle without in any wise mutilating the body or frame for the accommodation of the apparatus.

Having thus described my invention, what I claim as new and desire to secure by Letters Patent of the United States, is:

1. A heating apparatus for automobiles, embodying parallel communicating heater pipes arranged transversely of the vehicle above the floor of the same, a non-inflammable shield around and spaced from the heater pipes and open on the rear side for the passage of heated air, brackets for supporting said shield and heater pipes above the vehicle floor, a foot rest bar carried by the brackets, a duct for the exhaust gases from the engine communicating with the heater pipes, and means for controlling the passage of heated gases to the heater pipes.

2. A heating apparatus for automobiles, embodying a duct for the passage of exhaust gases, heater pipes in communication with said duct and arranged transversely of the vehicle above the floor of the same, end brackets forming the supports for the heater pipes, a metal shield around the heater pipes and having an opening on the rear side, a foot rest bar above said opening, and means for controlling the passage of gases to the heater pipes.

3. In a heating apparatus for automobiles, the combination with the parallel heater pipes connected for the circulation of the exhaust gases from the motor, of a sheet metal shield surrounding said heater pipes and having an opening in one side for the circulation of air about the pipes, end brackets on which the shield is mounted, a foot rest bar mounted on said brackets and extending parallel with and forming a support for the upper edge of the shield, and a reinforcing bar for the lower edge of the shield also mounted in said bracket.

4. In a heating apparatus for automobiles, the combination with the parallel connected heater pipes and sheet metal shield

surrounding said pipes and having an opening at one side for the circulation of air about the pipes, of end brackets on which the shield is mounted, and a foot rest bar 5 rigidly connecting said brackets and extending parallel with and in proximity to the upper edge of the shield, whereby said shield is protected from injury and the feet

of the passengers are supported in position to obtain the benefit of the heated air from 10 the heater.

LESTER O. NAYLOR.
